United States Patent Office

Des. 217,278
Patented Apr. 21, 1970

217,278

BASKET FOR FRUIT OR THE LIKE

Shelia M. Chandler, Baton Rouge, La., assignor to Textron Inc., Providence, R.I.

Filed July 3, 1968, Ser. No. 12,606

Term of patent 14 years

Int. Cl. D7—01

U.S. Cl. D44—15

FIG. 1

FIG. 3

FIG. 1 is a top plan view of a basket for fruit or the like showing my new design,

FIG. 2 is an elevational view from the bottom of FIG. 1 of the front half of the bowl; and

FIG. 3 is a bottom plan view.

I claim:

The ornamental design for a basket for fruit or the like, as shown.
